CONTROLLING DEVICE

Roy O. Allen, Athens, Pa., assignor to Ingersoll-Rand Company, New York, N. Y., a corporation of New Jersey

Application February 5, 1942, Serial No. 429,607

1 Claim. (CL 121—35)

This invention relates to fluid actuated tools, and more particularly to a controlling device for a fluid actuated riveting machine of the percussive type having a mounting to slidably support the riveting machine with respect to the work.

One object of the invention is to assure uniformity of the shapes of the portions of the rivets formed by the machine.

Another object is to prevent deformation of the work piece.

Another object is to obviate the chances of operating the machine longer than is actually necessary to perform the work of upsetting a rivet.

Other objects will be in part obvious and in part pointed out hereinafter.

In the drawings accompanying this specification and in which similar reference numerals refer to similar parts,

Figure 1 is a longitudinal side elevation of a riveting machine having the invention applied thereto,

Figure 2 is a longitudinal elevation, partly in section, of a riveting machine embodying the invention and showing the power unit of the riveting machine in one of its limiting positions and taken through Figure 1 on the line 2—2,

Figure 3 is a transverse view taken through Figure 1 on the line 3—3 showing a detail,

Figure 4 is a view similar to Figure 2 showing the power unit of the riveting machine in position for upsetting a rivet,

Figure 5 is a transverse view taken through Figure 2 on the line 5—5, and

Figure 6 is a similar view taken through Figure 5 on the line 6—6.

Referring more particularly to the drawings, 20 designated a fluid actuated power unit shown as being in the form of a riveting machine and 21 a sample of work upon which the riveting machine may operate.

The riveting machine is arranged slidably in a casing 22 having a bracket 23 fastened to the forward portion thereof, as by bolts 24, to support the work 21. An arm 25 of the bracket 23 extends into the path of the riveting machine and contains an anvil block 26 having a recess 27 to accommodate the pre-formed head of a rivet 28 extending through the work 21.

The riveting machine 20 may be of a known type and comprises, as casing parts, a cylinder 29 and a head block 30 threadedly connected thereto. The cylinder has a piston chamber 31 for the accommodation of a hammer piston 32 reciprocable in the piston chamber 31 for actuating a

rivet set 33 supported by a holder 34 the stem 35 of which extends slidably into the front end of the cylinder to receive the blows of the hammer piston 32. The holder 34 is yieldingly held in position to receive the blows of the hammer piston by a tool retainer 36 in the form of a coil spring threaded upon the forward portion of the cylinder 29 and having an end coil 37 acting as an abutment for an external shoulder 38 on the holder 34.

A valve 39 is arranged in the head block for distributing pressure fluid to the piston chamber. The pressure fluid thus distributed is conveyed to the valve mechanism by passages 40, in the head block 30, communicating with the rearward end of the chamber or bore 41 in the casing 22 wherein the riveting machine is slidably arranged. The piston chamber 31 may be provided with a suitable exhaust port (not shown) for conveying the exhaust fluid to the atmosphere.

In the periphery of the head block 30 is a sealing ring 42 to prevent the leakage of pressure fluid from the bore 41, and in the forward portion of the bore is a spring 43 that seats with its front end against a shoulder 44 on the casing 22 and with its other end against a shoulder 45 on the cylinder 29.

The riveting machine, when idle, is held in its rearmost limiting position in the casing by the 30 spring 43 and is actuated to the different working positions relatively to the casing by pressure fluid. To this end the casing 22 is provided with a bore 46 of small diameter as compared with that of the bore 41 into which it opens at its front end, and in the bore 46 is a plunger 47 that seats against the rearward end of the head block 30 and has a pressure surface 48, on its rearward end, that is subjected to pressure fluid for moving the riveting machine forwardly in the casing 22.

The pressure fluid applied to the pressure surface 48 and to a pressure surface 49 on the rearward end of the head block 30 is controlled by a throttle valve 50, of the poppet type, arranged in a valve chamber 51 in the rearward portion of

45 the casing 22. The valve chamber contains a bushing 52 the bore 53 of which serves as a guiding surface for the stem 54 of the valve 50. At one end of the bore 53 is a tapered seat 55 for the valve 50, and a spring 56 interposed between 50 the valve 50 and a plug 57 threaded into the end of the valve chamber 51, to seal it, normally presses the valve against the seat 55.

The pressure fluid intended to be controlled by the valve 50 may be introduced into a chamber 58 in the rearward end of the casing 22 by a

suitable supply conduit (not shown) and is conveyed from the chamber 52 to the valve chamber 51 by a passage 55 in the casing. In the periphery of the stem 54 adjacent the valve 50 is an annular groove 60 through which pressure fluid flows, in the open position of the valve 50, to a supply passage 61 leading from the bore 53 to the rearward end of the bore 46. The groove 60 is of suitable length so that it will be at all times in communication with the passage 61 irrespective of the position of the valve, and with an atmospheric exhaust port 30', in the bushing 52 and the casing, in the closed position of the valve 50.

The valve stem 54 also has a central passage 62 extending longitudinally therethrough and communicating with the annular groove 60 through radial ports 63 so that when the valve 50 is unseated to supply pressure fluid to the supply passage 61 pressure fluid will also flow through the ports 63 into the passage 62. In the wall and near the free end of the stem 54 are ports 64 that afford communication between the passage 62 and an annular groove 65 in the periphery of the stem 54 adapted to register with a supply passage 66 in the casing 22 and leading to the chamber 41.

The annular groove 65 is so located upon the stem 54 that a considerable degree of movement of the valve 50 may take place before said annular groove will register with the supply passage 66. Owing to this arrangement the bore 46 may be fully charged to cause the plunger 47 to move the power unit forwardly in the casing 22 for pressing the rivet set 33 against the rivet 28 before the annular groove 65 will register with the supply passage 66 for delivering pressure fluid to the pressure surface 49 and to initiate operation of the riveting machine.

The exhaust of pressure fluid from the bore 46 is also controlled by the throttle valve and the stem 54 accordingly has an annular groove 67 located between the annular grooves 65 and 60 to afford communication between the supply passage 66 and an atmospheric exhaust port 68 in the bushing 52 and the adjacent portion of the casing 22. The ends of the passages 66 and 68 that open into the bore 53 lie in different transverse planes so that when the annular groove 65 is in communication with the passage 66 the portion of the bore 53 lying between the annular groove 65 and the passage 68 will be blanked-off to prevent the loss of pressure fluid directly from supply to the atmosphere.

As is customary, the throttle valve 50 is unseated by manual force for valving pressure fluid to the riveting machine but means are provided to automatically cut-off the admission of pressure fluid and thereby stop the operation of the riveting machine as soon as the rivet has been suitably upset. To these ends the tool is equipped with a rod 69 that is journaled in lugs 70, three in the present instance, arranged at spaced points along the length of the casing 22. The rod 69 is both rotatable and slidable in the lugs 70 and carries, a valve lifter 71 comprising a hub 72, keyed to the rod, and a laterally extending wing 73 to engage the end 74 of the valve stem 54 projecting from the bore 53.

The valve lifter 71 is adjustable endwise of the rod 69 and such movement in a rearward direction is limited by a nut 78 threaded upon the rod 69 to enable the valve lifter to be shifted endwise of the rod. The opposite end of the valve lifter seats upon an end of a spring 75 encircling the

rod 69 and seating against the adjacent lug 70. The spring 75 acts constantly to push the rod 69 rearwardly to maintain the wing 73 in the longitudinal plane of the end 74 of the valve stem.

The rod 69 may be conveniently rotated by a lever 76 clamped to the rod by a screw 77, and the portion of the rod 69 forwardly of the foremost lug 70 is bent inwardly to form an arm 78 that extends through an opening 79 in the wall of the casing and part way into the bore 41. Preferably a flattened surface 80 is formed on the side of the arm 78 confronting the adjacent lug 70 and on the head block 30 is an annular shoulder 81 to engage the flattened surface 80 for sliding the rod 69 forwardly in the lugs 70.

The opening 79 is of suitable proportions so that the arm 78 may swing freely and move within a required range in an axial direction without interference and its rearward limiting position is determined by the lever 76 which may abut the forward surface of the intermediate lug 70 for that purpose. A spring 82 interposed between the lever 76 and the casing 22 normally holds the lever in an elevated position so that when the spring 75 acts to move the rod 69 rearwardly the wing 73 may move into position for engagement with the valve stem 54 without interference by said valve stem.

In the operation of the device and with the wing 73 of the valve lifter overlying the end of the valve stem 54 the rod 69 is rotated, by means of the lever 76, to unseat the valve 50. During the initial opening movement of the valve 50 pressure fluid will flow through the annular groove 60 and the supply passage 61 into the bore 46 against the pressure surface 48 and move the riveting machine forwardly in the casing to place the rivet set 33 into contact with the rivet 28.

When the work has been correctly located with respect to the rivet set the valve 50 is further depressed until the annular groove 65 registers with the supply passage 66. Pressure fluid will then flow into the bore 41 against the pressure surface 48 to assist in pressing the riveting machine forwardly toward the work. At the same time pressure fluid flows through the ports 40 and is distributed by the valve 39 to the piston chamber for actuating the hammer piston 32.

During the ensuing operation of upsetting the rivet the riveting machine moves gradually forwardly in the casing 22 and shortly prior to the completion of the work the shoulder 81 engages the arm 78 and carries the rod 69 forwardly until the valve lifter is moved out of the plane of the end 74 of the valve stem to release the valve. The spring 56 will then move the valve 50 against the seat 55 and cut-off the flow of the pressure fluid to the bores 46 and 41.

The pressure fluid in the bore 41 will then be exhausted through the distributing and percussive elements of the machine, and in the new position of the valve 50 the groove 67 will place the passage 66 in communication with the exhaust passage 68 so that pressure fluid will also be exhausted from the bore 46. The groove 60 will then also be in position to communicate the passage 61 with the port 60' to provide an escape for pressure fluid from the bore 46. At the same time the spring 43 will move the riveting machine or power unit rearwardly to its initial position. The spring 75 will move the rod 69 simultaneously rearwardly until the arm 78 engages the surface 82 of the opening 79 so that the valve lifter will again be in position for engagement with the valve stem 54.

In practice, the present invention has been found to be a highly satisfactory means for assuring the correct formation of the upset portions of the rivets and to prevent the operation of the riveting machine in excess of the time required for correctly upsetting the rivet.

I claim:

A fluid actuated tool, comprising a casing, a power unit slidable in the casing and having a pressure surface, a poppet valve for controlling the flow of pressure fluid to the pressure surface for driving the power unit forwardly in the casing, a rod slidable and rotatable on the casing, a valve lifter on the rod to overlie the end of the

valve and to rotate with the rod relatively to the valve, a lever on the rod for manually rotating the rod to cause the valve lifter to unseat the valve and holding the valve thus for admitting pressure fluid to the pressure surface, means on the rod to extend into the path of movement of the power unit and actuated by the power unit during the forward movement of the power unit in the casing for moving the valve lifter out of the plane of the end of the valve to release the valve, and a spring to return the valve to its seat for cutting-off the flow of pressure fluid to the pressure surface.

ROY O. ALLEN.
